CLAIM

The ornamental design for a snap top tote apparatus design, as shown and described.

DESCRIPTION

FIG. 1 is a front elevational view of a snap top tote apparatus showing our new design;

FIG. 2 is a top plan view thereof;

FIG. 3 is a left side elevational view thereof;

FIG. 4 is a right side elevational view thereof;

FIG. 5 is a rear elevational view thereof;

FIG. 6 is a bottom plan view thereof;

FIG. 7 is a perspective view thereof with a bottle inserted;

FIG. 8 is a front elevational view thereof;

FIG. 9 is a top plan view thereof;

FIG. 10 is a left side elevational view thereof;

FIG. 11 is a right side elevational view thereof;

FIG. 12 is a rear elevational view thereof; and,

FIG. 13 is a bottom plan view thereof.

The broken line showing of stitching and bottles is for illustrative purposes only and forms no part of the claimed design.
